DIRECTION FINDING DEVICE

Michael Ercolino, Wanamassa, N. J., assignor to
the United States of America as represented by
the Secretary of the Army

Application September 2, 1949, Serial No. 113,891

14 Claims. (Cl. 343—113)

(Granted under the act of March 3, 1883, as
amended April 30, 1928; 370 O. G. 757)

1

The invention described herein may be manufactured and used by or for the Government for governmental purposes, without the payment of any royalty thereon.

The present invention relates to improvements in the art of direction finding and sensing equipment and methods, and is a device that can be attached to a radio receiver for determining the direction to any transmitter of radio frequency energy at the frequency to which the receiver is tuned provided that the receiver is within the effective range of the transmitter.

The object of this invention is to provide a very simple and readily portable direction finding antenna of reasonable accuracy.

It is a further object of this invention to provide a manually operated dipole antenna, providing two response patterns.

It is a further object of this invention to provide a wide band, dipole antenna with means for producing both a figure of eight and a cardioid response pattern.

This invention is particularly applicable for use with the Signal Corps receiver SCR-300 to provide direction finding and sensing without appreciably decreasing the portability of the set.

Fig. 1 of the accompanying drawings shows the general physical appearance of the apparatus used in connection with applicant's invention;

Fig. 2 shows the structure and wiring of the device in detail, the antenna and associated receiver being shown only in part to save space;

Figs. 3 and 4 show the thumb switch in cross section.

The apparatus as shown in Fig. 1 consists of a handle 1 supporting a mounting dielectric framework 2 that supports the two antenna elements 3 and 4 of a folded dipole, and a thumb switch 5. The handle 1 is used to manually hold this antenna device and to rotate it in any desired direction. This handle is also mountable on the radio receiver 6 by means of a bracket 7 so that it can be held in any desired direction while an azimuth reading is taken.

The dipole elements 3 and 4 are adjustable in length, and are calibrated for setting to one-quarter wave length of the signal to be received, within the limits of the bands of frequencies to be covered. These dipole elements 3 and 4 are arranged to a broad based V formation with approximately a 60° included angle. This provides a wider band coverage than a normal dipole would give and provides maximum receptivity of vertically polarized signals. A coaxial cable 10 is attached from framework 2 to bracket 7 which serves also as a connector to receiver 6.

The circuit connections and their physical inter-relation are seen in Fig. 2 which shows the reverse side of Fig. 1. In Fig. 2, one element, 3, of the dipole connects through metal support 22 to the center element 11 of the coaxial cable 10,

the other end of this center element being connected to the antenna socket 12 of the radio receiver 6. The other element 4 of the dipole connects through metal support 23, and through switch 5 to the shield 13 of the coaxial cable 10, the other end of the shield connecting to the ground terminal 14 of the radio receiver 6 by a connector 15.

Figs. 3 and 4 show the switch 5 in cross section. 10 The switch is in its normal, closed position in Fig. 3 and is open, as if depressed, in Fig. 4. The switch 5 consists of a flat metal plate 16 having a hole 17 through which a metal button 18, carried by a flat spring 19 projects slightly. The flat spring 19 is connected to element 4 through the metal support 23 and the plate 16 is connected to the shield 13 of the coaxial cable 11. When at rest, the metal button 18 is connected to the plate 16 as in Fig. 3, thereby connecting 15 the dipole element 4 to the shield 13 of coaxial cable 11. When the metal button is depressed, as in Fig. 4, the circuit between button 18 and plate 16 is open.

The switch 5 is placed so as to be conveniently 20 depressed by the operator's thumb and is so designed that, while the switch is depressed, the operator's thumb forms a resistance connection between the button 18 and the plate 16. At the same time, the antenna effect of the operator's 25 body is added to the ground input of the receiving set 6 through the metal button and cable. These changes alter the effect of dipole element 4 and the input to the radio receiver. When the switch is depressed by a thumb the response pattern is a cardioid, with maximum signals in the plane of the dipole elements in the direction of the dipole element that has no switch and a minimum in the opposite direction. For convenience 30 in sensing the framework may have an arrow 20 or similar marker which indicates the general direction of the transmitting station for a maximum signal. When the switch is released the response pattern is a figure 8 with a null of receptivity in each direction normal to the plane of the element. For accurate direction finding, 35 sighting means 21 is provided, the angle of this sighting means being accurately adjusted to correspond to the null.

When the apparatus is rotated without the 40 switch depressed, while a signal is being received, two nulls of receptivity are apparent. These are sharp nulls that define the direction of the transmitter within a few degrees. However, this 45 does not indicate in which of the two null directions the transmitter lies.

Sensing the true direction of the transmitter 50 is accomplished by depressing the switch to determine the approximate direction of maximum receptivity, which distinguishes the correct null and avoids 180° ambiguity in determining the 55 azimuth of the transmitter.

The sensing arrangement alone could serve for direction finding, except that the cardioid pattern has neither a sharp maximum nor a sharp minimum of receptivity. Therefore it is desirable to use the arrangement that produces the figure of 8 pattern, that has sharp nulls, for an accurate direction determination.

In operation, the apparatus is connected to an appropriate receiver, one version of this apparatus, for example, is the Signal Corps Homing Device RC-300, already in use, that was designed for use with the Signal Corps Radio Receiver SCR-300. The operator holds the handle vertically and rotates it until the signal from the transmitter being located is at a minimum. The transmitter is then in one of the directions normal to the plane of the dipole elements. These directions are noted.

The switch is depressed by the operator's thumb, and the apparatus is rotated to the general direction of minimum response. This direction as indicated by the arrow approximates the previously determined null direction in which the transmitter lies.

Having actually established the direction of the transmitter, a more precise azimuth can be determined by mounting the apparatus on the attached bracket above the calibrated azimuth scale 25 and reading, at the null of reception, the azimuth in the direction of the transmitter previously determined.

What is claimed is:

1. A direction-finding antenna device comprising, two antenna elements combining to form a dipole antenna, each of said elements being respectively coupled to an input terminal of a radio receiving apparatus, and a switch, one of said antenna elements being coupled through said switch to its respective terminal, said switch upon being operated serving to include a resistance in series with said one element.

2. A device as in claim 1, wherein said switch is normally closed.

3. A direction-finding device as in claim 1, wherein said antenna elements respectively have a length of one quarter of the wave length being received.

4. A device as in claim 3 wherein each of said antenna elements consists of a plurality of concentric metal tubes that are collapsible into the said metal tubes.

5. A device as in claim 4 wherein each of said collapsible concentric metal tubes is calibrated to indicate the lengths of said antenna elements near the limit of their extension.

6. A direction-finding antenna device comprising, two antenna elements combining to form a dipole antenna, each of said elements being respectively coupled to an input terminal of a radio receiving apparatus, a normally closed switch, one of said antenna elements being coupled through said normally closed switch to its respective terminal, said switch opening to include a resistance, and a dielectric frame, the base of each of said antenna elements being mounted on said dielectric frame.

7. A device as in claim 6 with a handle attached to said dielectric frame.

8. A device as in claim 6, wherein said antenna has an overall length equal to one-half of the wave length of the radio signal to be received.

9. A device as in claim 6 with said switch mounted on said dielectric frame.

10. A device as in claim 9 with said switch consisting of a metal washer-like disc in contact

5 with a slightly projecting metal button, said metal disc serving to complete the electrical connection between said one element and its respective terminal.

11. A device as in claim 10 wherein depressing of said metal button by an uncovered human digit opens the electrical contact between said metal disc and said respective terminal, whereby body resistance is placed in series with said metal disc and said one element.

12. A direction finding device as in claim 6, said switch being mounted on said frame and consisting of a metal button connected to a metal washer-like disc, said disc being connected to one end of a flat metal spring, the other end of said spring being connected to the base of said one element, said flat spring serving to urge said washer-like disc in electrical contact with said respective input terminal of said radio receiving apparatus.

13. A device as in claim 12 with a coaxial cable attached to said dielectric frame, the shield of said coaxial cable being connected through said switch to said one antenna element, the center conductor of said coaxial cable being connected directly to the other of said antenna elements, the other ends of the conductors of said coaxial cable being respectively connected to said input terminals of said radio receiver.

14. A device for determining the direction of a radio transmitter using a radio receiver of appropriate frequency response, comprising two one-quarter wave adjustable dipoles mounted on a rotatable dielectric frame, one of said dipoles forming an antenna and connecting to the antenna terminal of said radio receiver, the other of said dipoles connecting through a switch to the ground terminal of said radio receiver, said switch consisting of a flat metal spring, and a metal button connected to and projecting slightly above the surface of a washer, said spring being connected at one end to said other of said dipoles and being in electrical contact with said washer at the other end thereof, said washer being urged in electrical contact with said ground terminal by said spring, whereby said antenna may be rotated with said button of said switch depressed by an operator's bare thumb which introduces the resistance of said thumb across said switch and adds the antenna effect of the operator's body to said other of said dipoles, the direction of maximum signal indicating the approximate direction of said transmitter, said switch then being released and said antenna rotated until a sharp null is observed in said direction of maximum receptivity with the switch depressed, said sharp null indicating the exact direction of the transmitter.
